UNITED STATES PATENT OFFICE.

FRANK H. CLARK, OF SARATOGA SPRINGS, AND ROBERT C. TURNBULL, OF TROY, NEW YORK.

CAR-COUPING.

SPECIFICATION forming part of Letters Patent No. 498,621, dated May 30, 1893.

Application filed January 11, 1893. Serial No. 458,097. (No model.)

To all whom it may concern:

Be it known that we, FRANK H. CLARK, residing at Saratoga Springs, Saratoga county, and ROBERT C. TURNBULL, residing at Troy, 5 Rensselaer county, New York, citizens of the United States, have invented a certain new and useful Improvement in Car-Couplings, of which the following is a specification.

As is well known, the car couplings, in use 10 to-day are liable to be torn from the cars to which they are secured by accident or otherwise, and, falling upon the track, to derail the car. Some means is therefore desired which shall act to prevent accidents of this character, and which shall preferably operate to first 15 uncouple the cars, and afterward to prevent the detached coupler from falling upon the track.

It is the object of our invention to provide 20 a device of this character, and, stated generally, we accomplish this object by providing the coupler with suitable mechanism adapted, when the coupler is torn from the car, to engage with the locking pin to release the hook 25 to unlock the coupler, and afterward to sustain such coupler and prevent its falling upon the track.

Our invention consists in the features, details and combinations hereinafter described 30 and claimed.

In the drawings, Figure 1 is a side elevation of a coupler provided with our improvements; and Fig. 2 a front elevation thereof.

The coupler, so far as the draw head A, 35 rotating hook B, and coupling pin C are concerned, may be made in any of the well known styles, which will enable the hereinafter described devices to act as set forth. We first attach to one side of the coupler, which may 40 be either side desired, a bell crank lever D, which is preferably so attached as to be capable of rocking in a substantially vertical plane, with one arm d extending upward, and with the other d' extending toward the car. 45 The arm d is securely connected to the car D² by means of a chain D', for the purpose hereinafter described. We then pivotally attach to the draw head, at any suitable point, a lever or hook E, preferably made in the form 50 shown, one end of this lever e being in engagement with the arm d' of the bell crank,

and the other or hooked end e' bearing against the coupling pin C. The form, dimensions and material of the bell crank D and lever E may be altered as desired, so long as they are 55 capable of co-acting to produce the desired result.

The device operates as follows: It should be understood that under normal conditions the bell crank lever, hook E, &c., remain inoperative. If now, however, the coupler be torn from the car, the chain will operate to draw the arm d of the bell crank toward the left (Fig. 1). The arm d' will then act to depress the end e of the pivoted hook lever, and 60 raise the end e', thereby raising the locking pin and allowing the rotating hook to swing open to separate from the coupler with which it is in engagement, after which the chain will act to sustain the coupler and prevent its 65 falling upon the track. We thus provide what may be called an "emergency device" for uncoupling the coupler and preventing accidents; and while we have described more or less precise forms, we do not intend to 70 unduly limit ourselves thereto, but contemplate changes in form and proportion, and the substitution of equivalent members as may be desirable or necessary. For example, it is not essential that the end of the locking 75 pin should extend below the draw head, as the form of the hook E may be so changed as to engage with the locking pin, the only essential feature being that such engagement should exist as will permit the above described 80 action to take place.

We claim—

1. A coupler provided with two levers engaging each other one lever contacting with the locking pin, and the other connected to a 90 point outside of the coupler, such levers being adapted to remain inoperative under normal conditions, but acting in case the coupler is detached from the car to raise the pin, release the hook, and prevent the coupler 95 from falling upon the track, substantially as described.

2. In a coupler provided with a locking pin, the combination of a bell crank lever pivoted to the draw head, a chain attached to one arm 100 of such lever and to the car, and a hook lever pivoted to the draw head, engaging with the

other arm of the bell crank and with the coupling pin, substantially as described.

3. The combination with a draw head provided with a rotating hook and a locking pin, of a bell crank lever pivoted at one side of the draw head, with the arms of the lever extending in substantially horizontal and vertical positions, a chain attached to the car and to the vertical arm of the bell crank, a hooked lever pivoted beneath the draw head, one arm of such lever engaging with the horizontal arm of the bell crank and the other arm impinging against the lower end of the locking

pin, whereby when the coupler is detached from the car, the chain will act on the vertical arm of the bell crank lever to rock the hook lever and raise the pin to release the rotating hook, thereby uncoupling the car, after which the chain will act to sustain the coupler and prevent its falling upon the track, substantially as described. 15 20
